Attorneys.

UNITED STATES PATENT OFFICE.

EMMA BURNS, OF ALLEGHENY, PENNSYLVANIA.

WASHBOILER.

SPECIFICATION forming part of Letters Patent No. 724,800, dated April 7, 1903.

Application filed October 10, 1902. Serial No. 126,699. (No model.)

To all whom it may concern:

Be it known that I, EMMA BURNS, a citizen of the United States of America, residing at Allegheny, in the county of Allegheny and State of Pennsylvania, have invented certain new and useful Improvements in Washboilers, of which the following is a specification, reference being had therein to the accompanying drawings.

This invention relates to certain new and useful improvements in washboilers; and the invention has for its primary object to construct a boiler having a dividing partition therein which separates the boiler into two compartments, and the invention aims to construct a boiler of this type with means for preventing danger of the water in one compartment splashing or boiling into the other compartment, and also to substantially prevent steam arising in one compartment from entering into the other compartment of the boiler.

To this end the invention consists in providing a washboiler with a partition which may be located either centrally thereof or toward one end of the boiler, so as to divide the boiler into two compartments. This partition is extended above the rim or upper edge of the boiler, and the upper end of the partition is substantially convex to conform to the lower face of the boiler lid or cover. This boiler lid or cover carries on its lower face a seat which receives the upper end of the partition and forms a seal therewith to prevent water or steam from one compartment passing to the other compartment.

In describing the invention in detail reference is had to the accompanying drawings, forming a part of this specification, and where-40 in like numerals of reference indicate like parts throughout the several views, in which—

Figure 1 is a central longitudinal sectional view of the washboiler constructed in accordance with my invention. Fig. 2 is a trans-45 verse vertical sectional view thereof. Fig. 3 is a vertical sectional view of a portion of the lid or cover, showing a transverse section of a portion of the partition and a modified form of seal. Fig. 4 is a like view of still another 50 modified form of seal.

To put my invention into practice, I pro-

vide a boiler 1 with a transverse partition 2, which may be securely soldered to the bottom and to the sides of the boiler 1 and may be located centrally of the boiler or toward one 55 end thereof, as may be desired. This partition 2 is of a greater height than the boiler, the upper end thereof extending beyond the upper edge or rim of the boiler and being shaped to conform to the lower face of the 60 lid or cover 3. This lid or cover has secured by suitable means to its lower face a seat or shield 4, which receives the upper end of the partition 2. This seat or shield forms a seal with the upper end of the partition 2 and pre- 65 vents the water and also practically prevents the steam from one compartment passing to the other compartment of the boiler. This seat or shield is preferably so constructed as to be provided with inclined inner and outer 70 walls, whereby any water splashing upon the same will readily drain off.

In Fig. 3 I show a partition 2', constructed at its upper end with a bead 3' for engagement with the seat or shield, the latter being 75 of the same form of construction as shown in Figs. 1 and 2, and in Fig. 4 I show a partition 2^a, provided at its upper end with a substantially inverted-V-shaped strip 2^b, which is secured to the upper end of said partition and 80 which fits within a correspondingly-shaped seat or shield 2^c, carried by the lid or cover 3.

With this construction of boiler, the two compartments being effectually separated one from the other, the coarser clothes may be 85 placed in one compartment and the finer clothes in the other compartment, whereby they may be subjected to the cleansing process at the same time without any danger of the finer fabrics being injured by the coarser 90 ones.

Although I have shown the partition arranged substantially centrally of the washboiler, yet in practice I prefer to provide one of the compartments of a slightly-greater size 95 than the other, and to this end the partition will be arranged adjacent to one end of the boiler.

In the practice of my invention it will be noted that various changes may be made in 100 the details of construction without departing from the general spirit of my invention.

Having fully described my invention, what I claim as new, and desire to secure by Letters Patent, is—

5 In combination with a boiler having a partition dividing the same into two compartments and extending above the upper edge or rim of the boiler, of a lid or cover, a seat secured thereto, said seat formed of a single sheet of metal bent to approximate U shape,

the edges of said seat extending outwardly, to substantially as described.

In testimony whereof I affix my signature in the presence of two witnesses.

EMMA BURNS.
